UNITED STATES PATENT OFFICE.

WILLIAM R. HOWARD, OF ESTHerville, IOWA.

BEET HARVESTER.

Application filed October 2, 1920. Serial No. 414,360.

To all whom it may concern:

Be it known that I, WILLIAM R. HOWARD, a citizen of United States, residing at Estherville, in the county of Emmet and State of Iowa, have invented new and useful Improvements in Beet Harvesters, of which the following is a specification.

This invention relates to beet harvesters and embodies amongst other features, a novel construction of means for topping the beets, the latter being conveyed through a wagon or the like adjacent the harvester, while the tops are deposited upon the ground.

15 A still further object of the invention, resides in the provision of means for adjusting the cutting elements for the tops of the beets, to regulate the depth of the cut.

Other objects and advantages will appear 20 from the following detailed description when taken in connection with the accompanying drawings, the invention residing in the construction, combination and arrangement of parts as claimed.

25 In the drawings forming part of this application, like numerals of reference indicate similar parts in the several views, and wherein:

Figure 1 is a side elevation of the machine forming the subject matter of my invention.

Figure 2 is a view looking from the opposite sides of the machine.

Figure 3 is a top plan view.

Figure 4 is a sectional view taken on line 30 8—8 of Figure 3 and showing the top severing mechanism.

Figure 5 is a plan view of Figure 4.

Figure 6 is a sectional view taken on line 10—10 of Figure 5.

40 The machine forming the subject matter of my invention comprises a main frame indicated at 10, and mounted on wheels at 11. The frame may be of any suitable construction including upper and lower side members 45 as shown. The machine may be propelled in any suitable manner or it may be drawn over the ground or surface by means of a tractor not shown. The machine is also steered through the instrumentality of a steering wheel 12 and steering mechanism of usual construction.

50 A semi-floating frame is indicated at 14, the latter being pivoted between the upper side bars of the main frame as at 15. Journaled between the sides of the semi-floating frame 14 is a wheel 16.

As shown, the beets are released from the claws 20, when the beets assume a position immediately above the receptacle 60, into which the beets are deposited and wherein 60 the tops of the beets are severed.

Projecting from within the receptacle 60 in the direction of the wheel 16, is a tangentially disposed finger 61, equipped with a roller 62 disposed to be received within 65 grooves 63 formed in the periphery of the wheel 16. The purpose of this finger is to positively separate the beet from between each pair of gripping claws as the latter approach the receptacle 60. When so separated, the beet or beets fall into the receptacle and repose upon the curved arms 64 and also upon an adjustable gage 65 for the cutting disk 66. This disk is journaled in 70 bearings 67 depending from the fingers 61 75 and is disposed vertically or in other words at right angles to the cutting disk 68. The purpose of the cutting disk 66 is to separate and loosen the tops of the beets, while the disk 68 completely severs these tops as the 80 beets continue to move over the finger 61 onto the plate 69, from where the beets are 85 conveyed into a chute 70. The gage 65 is pivoted as at 71 for vertical adjustment, this gage regulating the depth of the cut made by the disk 66. The gage is provided with slots 74 for the reception of fastening elements 73 which maintain the gage fixed relative to the finger 61 in its given position. The disks 66 and 68 respectively are actuated in unison 90 by means of suitable gearing such as shown in Figure 8, the latter being operated from one of the tractor wheels 11 of the machine.

95 Endless chains 54 and 75 are embodied in this driving connection for the cutting disks 66 and 68. After the tops have been severed from the beets, the beets are directed into the chute 70 from where they are conveyed to a wagon or the like 76 arranged at one side 100 of the machine. The tops are also conveyed to the chute 70 but are deposited therefrom upon the ground at one side of the machine.

105 While it is believed that from the foregoing description the nature and advantages of the invention will be readily apparent, I desire to have it understood that what is herein shown and described is merely illustrative of one embodiment of the invention to which I do not limit myself, and that such changes may be resorted to when 110 desired as fall within the scope of what is claimed.

What is claimed is:—

1. A beet harvester comprising a portable frame, a beet receiving receptacle, means within the receptacle for severing the tops of said beets, and said means including right angularly disposed cutting elements.
2. A beet harvester comprising a portable frame, a beet receiving receptacle, means within the receptacle for severing the tops from the beets, said means including right angularly disposed cutting elements, and means for actuating said elements upon movement of the machine over the ground.
3. A beet harvester comprising a portable frame, a beet receiving receptacle, means within the receptacle for severing the tops of said beets, and said means including right angularly disposed cutting disks.
4. A beet harvester comprising a portable frame, a beet receiving receptacle, means within the receptacle for severing the tops of the beets, said means including right angularly disposed cutting disks mounted for rotation and actuated in unison.
5. A beet harvester comprising a portable frame, beet receiving receptacle, means within the receptacle for severing the tops of the beets, said means including right angularly disposed cutting elements mounted for rotation, a gage for regulating the depth of the cut made by one of said elements, and means for actuating said elements upon movement of the machine over the ground.
6. A beet harvester comprising a portable frame, a beet receiving receptacle, means within the receptacle for severing the tops of said beets, said means including right angularly disposed cutting disks mounted for rotation, means for actuating said disks in unison, and means for regulating the depth of the cut made by one of said disks.
7. A beet harvester comprising a portable frame, a beet receiving receptacle, and means within the receptacle for severing the tops of the beets, said means including right angularly disposed cutting disks mounted for rotation.

In testimony whereof I affix my signature.

WILLIAM R. HOWARD
